DELAY ACTION DETONATOR AND FUSE AND DELAY COMPOSITION FOR USE THEREIN

Charles Edwin Sosson, Ardrossan, Scotland, assignor to Imperial Chemical Industries Limited, a corporation of Great Britain

Application August 27, 1936, Serial No. 98,255
In Great Britain August 29, 1935

10 Claims. (Cl. 102—10)

The present invention relates to the manufacture of delay action detonators and fuses and especially to the compositions used as the delay element therein. More particularly the invention relates to that type of delay action detonator or fuse in which little or no gas is given off in the course of the combustion of the delay composition and in which the delay composition is totally enclosed during its combustion.

10 Delay action detonators and fuses of this type not only obviate any risk of the explosive cartridge being prematurely ignited by contact with flame or hot particles ejected during the combustion of the delay composition, but are particularly adapted for use in fiery or dusty mines in which it is important that hot products of combustion from the delay composition should not be allowed to come into contact with the adjacent atmosphere.

15 It has been proposed in the manufacture of electric delay action fuses of all kinds which are totally enclosed, to employ as delay elements compositions containing metals and oxidizing agents. Amongst the particular compositions suggested 20 was a mixture of equal parts of antimony and potassium permanganate, it being stated that in this composition the antimony is completely oxidized on ignition. Mixtures containing other materials have also been proposed. Some of 25 these compositions tend to become insensitive to ignition by the fusehead on storage at raised temperatures even under dry conditions, and while the above-mentioned composition consisting of antimony and potassium permanganate is satisfactory in this respect it is not very easily ignited 30 in the delay element. Relatively slow burning compositions of the kind described which can be ignited sufficiently readily, and which maintain their ignitability on storage are, therefore, difficult to obtain.

35 The object of the present invention is a new and improved substantially gasless ignition composition. A further object is an ignition composition of the character described which is readily ignitable as prepared and maintains its ignitability on storage. A still further object is a ventless delay electric blasting initiator provided 40 with an improved substantially gasless delay ignition composition. Other objects will be apparent as the invention is hereinafter more fully described.

45 I have found that these objects are accomplished by incorporating a proportion of zinc in an ignition composition comprising antimony and potassium permanganate. According to the pres-

5 ent invention a composition for use in delay action detonators and fuses consists of a substantially gasless mixture containing antimony, zinc, and potassium permanganate. The proportion of zinc is preferably between about 5 and 25% by weight of the mixture, and the proportion of the metals in the mixture is not less than that which is required to reduce the potassium permanganate in accordance with the following equations:

10 The presence of the zinc not only facilitates the ignition of the antimony-potassium permanganate mixtures, but also tends to increase their 15 burning speed, and in order to compensate for this the proportion of potassium permanganate may be reduced somewhat below the amount which would theoretically be required according to the above equations to oxidize the metals, but 20 will not usually be less than about the combined weights of the metals. A low percentage of an inert material such as lead chromate or zinc oxide may be introduced into the mixture in order further to modify its burning speed.

25 In preparing the delay element, the composition may be filled into a lead tube of somewhat greater diameter than will fit into place in the delay action device, and the tube may then be drawn out to reduce the diameter and compress 30 the powder. The compositions of the present invention are possessed of good sensitiveness to ignition, and when introduced into a lead tube which is subsequently drawn to an internal diameter of 4 mm. and placed in close proximity to 35 a fusehead such as one of those described in specification No. 428,872, they ignite satisfactorily. They may also be stored at raised temperatures, for instance at 50° C., without appreciable deterioration so long as they are kept quite dry, but 40 the compositions are liable to deteriorate when submitted to hot storage in moist atmospheres. It is therefore important that the detonators or fuses in which they are used should be so constructed that moisture cannot enter into them 45 from surrounding moist atmospheres during service conditions or storage. It is unnecessary in constructing delay detonators according to the invention to take special precautions to exclude the atmosphere from the detonator during assembly, since the free air space in the assembly will normally be very small.

50 The construction of a delay action detonator according to the invention is illustrated in the accompanying drawing, which is a vertical mid-

section of a detonator. The detonator tube 1 is provided with a main charge 2 on to the top of which is pressed a drawn lead tube 3 containing the charge 4 of the composition containing antimony, zinc and potassium permanganate. A low tension gasless type of fusehead 6 with its fire-proof paper shield 5 is positioned in the detonator tube so that the bead 7 of the fusehead is in close proximity to one end of the delay composition. The sealing arrangement consists of the rubber plug 8 and a bituminous sealing composition 11 poured on top of the rubber plug and completing the hermetic seal. The lead wires 9 pass through the plug 8 and the composition 11 as shown and the wall of the tube 1 is crimped at 10 to secure the plug in position.

The invention is further illustrated by the following examples. The parts and proportions are by weight.

20

Example 1

A mixture of 1 part lead chromate and 20 parts of a mixture of antimony, zinc and potassium permanganate in the proportions 36:10:54 (prepared from the powdered materials passing a 100 mesh British standard testing sieve) is filled into a lead tube which is subsequently drawn through a die and inserted into a detonator as illustrated in Figure 1. The delay period of the composition is approximately two seconds per centimetre.

Example 2

A mixture of 30 parts of antimony, 15 parts of zinc and 55 parts of potassium permanganate (prepared from the powdered materials passing an 80 mesh (British standard testing sieve) is filled into a lead tube which is subsequently drawn through a die and inserted into a detonator as illustrated in Figure 1. The delay period of the composition is approximately two seconds per centimetre.

In the foregoing detailed description of my invention it is apparent that many variations in detail may be made without departing from the spirit and scope thereof. Thus, for example, other types of electric firing means may be employed, such as the usual type of concave plug or the like. Furthermore, other oxidizing agents may be employed in place of potassium permanganate, for example potassium chlorate or perchlorate, sodium dichromate, calcium peroxide, barium peroxide and the like. Permanganate is preferred, however, since the composition burns more regularly and the products of combustion

are substantially gasless. And finally, although I have illustrated the application of my improved ignition composition to delay blasting initiators, it is apparent that the same composition may be employed to advantage in time ring fuses of military shells. Other variations will be apparent to any one skilled in the art. I intend, therefore, to be limited only in accordance with the following patent claims.

10
I claim:

1. In an electric blasting initiator a substantially gasless ignition composition comprising zinc, antimony, and an oxidizing agent.
2. In a delay electric blasting initiator a substantially gasless delay ignition composition comprising zinc, antimony, and potassium permanganate.
3. In a delay electric blasting cap a substantially gasless delay ignition composition comprising zinc, antimony, and potassium permanganate.
4. In a delay electric blasting cap a substantially gasless delay ignition composition comprising zinc, antimony, potassium permanganate, and an inert material.
5. In a ventless delay electric blasting cap a substantially gasless delay ignition composition comprising zinc, antimony, and potassium permanganate.
6. In a ventless delay electric blasting cap containing a detonating base charge, a delay element containing a substantially gasless ignition composition comprising zinc, antimony, and potassium permanganate, and an electric firing means.
7. In a ventless delay electric blasting cap comprising a closed metal shell, a detonating base charge, and an electric firing means, a substantially gasless delay ignition composition comprising zinc, antimony, and potassium permanganate.
8. In a ventless delay electric blasting cap, comprising a closed metal shell, a detonating base charge, and an electric firing means, a substantially gasless delay ignition composition comprising zinc, antimony, potassium permanganate, and an inert material in an amount sufficient to modify the burning speed thereof.
9. The ignition composition of claim 8, in which said inert material comprises zinc oxide.
10. The ignition composition of claim 8, in which said inert material comprises lead chromate.

35
CHARLES E. SOSSON.
